DESIGN FOR A TABLE

James Mont, New York, N. Y.

Application February 5, 1947, Serial No. 136,712

Term of patent 7 years

(Cl. D33—14)

To all whom it may concern:

Be it known that I, James Mont, a citizen of the United States of America, residing in New York, county of New York, and State of New York, have invented a new, original, and ornamental Design for a Table, of which the following is a specification, reference being had to the accompanying drawing, forming part thereof.

The figure on the drawing is a perspective view of a table showing my new design. The opposite side presents substantially the same appearance as that shown on the drawing.

I claim:

The ornamental design for a table, substantially as shown and described.

JAMES MONT.
